UNITED STATES PATENT OFFICE.

JOHN Q. SHERMAN, OF DAYTON, OHIO.

MANIFOLDING PAPER.

Application filed March 11, 1921. Serial No. 451,626.

To all whom it may concern:

Be it known that I, JOHN Q. SHERMAN, a citizen of the United States, and a resident of the city of Dayton, in the county of Montgomery and State of Ohio, have invented certain new and useful Improvements in Manifolding Paper, of which the following is a full, clear, and exact description, reference being had to the accompanying drawings, forming part of this specification.

My invention relates to improved methods of punching manifolding papers, so as to present a series of holes for engagement by 15 aligning pins, said pins normally serving to both align and feed a plurality of webs of paper.

The paper employed in my invention is preferably employed with some such mechanism as is shown and described for the first time in the patent to Schirmer No. 940,481, dated November 16, 1909, wherein an autographic register is described having rotary pin bearing bodies and certain other mechanisms adapted to store and support a plurality of continuous webs of paper.

There are many other forms of feed pin manifolding devices, however, and my invention may be employed with any devices 30 wherein pins are moved through a path adapted to feed and align a plurality of webs of paper.

The usual manner of printing and cutting the webs of paper for use in manifolding machines, is to print up a wide web in a press and punch the holes therein, while printing is being done, and then slit the web into the desired number of forms. In this way a certain degree of accuracy is 40 maintained, so that all of the sections of the paper will have forms printed thereon, in like positions.

However, due to the nature of the paper itself, and varying conditions of its manufacture and of moisture and other atmospheric conditions and the like, it is not possible to obtain perfect accuracy either in printing, punching the holes, or slitting up the various forms, or in maintaining the proper and correct spacing between holes under different atmospheric conditions, so 50 that some will be wider than others in the

same cross section of a large web, and some longer than others. The discrepancies, in a single set of forms, are too slight to detract from their full manifolding value, but provision must be made for taking care of discrepancies each time they appear to prevent an accumulation of error, with a resultant mis-alignment.

Where only a few superimposed webs of paper are to be fed by means of traveling pins, the chance discrepancies may usually be taken care of by fair size punch holes and smaller pins, the size of the holes being such that the pins will readily enter them and not bind against their edges; but for a larger number of copies and often for a lesser number, the holes cut with due care will yet ride up on the pins and start a tearing of the paper. This may occur, as noted from the webs being of different lengths, the spacing of the holes of varying width for different superimposed webs and such like reasons.

If only one form was fed slight discrepancies in punching would not always prevent proper feed, but where several copies are fed, the discrepancies, particularly those that cause a variation between the various copies and thus make them differ from each other, will have the feed holes in some forms overlapped by non-punched portions of other forms. Where this occurs the sheets underneath the top sheet are held down by the top sheet, and, with the use of ordinary round feeding holes on either side, are not given a chance to adjust themselves because of the discrepancy in punching. When not held down by the top sheet, if the holes in the under sheets are punched too far apart, they would have a tendency to buckle; that is, the holes would be brought together and forced over the pins to a certain extent as when one copy is fed. The top sheet holding down the other copies, however, will keep them flat, thus causing the wider and narrower punched forms to overlap the feed holes of the properly punched forms, and the feed pins in the feeding operation will then punch through the non-punched portions of the improperly punched forms. This permits the pins to obtain a purchase on the forms and causes wrong feeding by the

forms immediately riding over the pins. The overlapping caused by differences in the various copies of a set of manifolding forms is the greatest difficulty to overcome in feeding them.

Discrepancies occur in goods, that have been manufactured perfectly, after they have been shipped, by changed atmospheric conditions that cause the forms to shrink when dry, or expand with increased moisture. The variations between various copies is particularly noticed at such times, especially where different colors, qualities and weights of paper are used in the same set; the extent of the variations from the standard or correct punching depending on the quality, weight and grades of stock, some of which are more susceptible to atmospheric conditions than others.

According to my invention, to avoid all difficulty due to this inaccuracy of printing that is un-controllable, so far as I am advised, I punch holes in the paper (in the proper relative position to the printing), which vary widely from exact similarity to the sizes of the pins, and so arrange them that one side or the other of the webs will be acting as aligning and feeding elements, while the other side will not interfere with this proper feed by acting in a different manner.

As will be noted I show many forms of structure for accomplishing my object, which same is accomplished by that certain construction and arrangement of parts to be hereinafter more specifically pointed out and claimed.

In the drawings,

Figure 1 is a plan view showing a pin wheel feed and a plurality of webs of paper thereon, punched as per my invention and illustrating the discrepancies and the manner of avoiding difficulties because of them.

Figure 2 is a like view showing a different sort of expanded pin hole.

Figure 3 is another view showing, in the same manner, a still different form, the feed in the three figures being in the direction of the arrows.

Figure 4 is a perspective view showing a series of webs punched as per the form shown in Figure 1, illustrating how one edge of a wide press strip may be looser than the other.

Figure 5 is a like view showing the same parts as in Figure 4 and showing how a crease in the press strip will throw the printing and punching out of true position.

Figure 6 is a plan view showing another arrangement of alignment holes.

Figure 7 is a plan view of still another arrangement.

It should be noted that the various forms of punching for manifolding paper shown in the above views are such as to provide

for a feeding at all times and an alignment at all times and do away with chances for the pins, which have a fixed spacing both laterally and longitudinally of the machine, to work into the paper at some non-apertured point.

The punching arrangement comprises different punchings or apertures, which I will designate as transversely elongated holes T, extra large round holes R, longitudinally extending holes L, and normal sized holes, such as will form a loose but accurate fit over the pins, as at N.

Taking up the various figures of the drawings, Figure 1 shows three webs of paper 1, 2, and 3, in which one margin is punched with holes T and the other margin with holes N.

The pin wheels 4 are on a shaft 5 and, as will be observed, the pins 6 at the holes N are in engagement with each web and in the act of feeding all three webs with the holes therein and the printing thereon in accurate registry.

The pins 7 on the other side are engaging in the holes T and the discrepancy in width of the webs is such that web 2 is narrower than web 1 and web 3 wider than web 2, so that the pins while engaging the "feeding wall" of each hole of each web, do not engage in the same part of the hole for each web by any means.

The feeding will, in such cases of discrepancy, progress without tearing the paper and both sets of holes will assist in the longitudinal alignment of the various webs of paper, while the set of holes N will do all of the transverse alignment.

The structure shown in Figure 2 comprises three webs of paper 1, 2, and 3, and the holes in one margin are of the type termed R, whereas the holes in the other margin are of the type termed N.

It can be appreciated that the large holes will permit of the same nature of self-adjustment over the pins as the holes T in the first form described. The "feeding walls" of the large holes R are preferably on the same transverse line as the like walls of the normal holes, the transverse line being what I may term the "feeding line."

Taking up next the form shown in Figure 3, it will be noted here that there are webs 1, 2, and 3, and that along the margin to the left of the webs, the holes are of the type T, while the other margin has holes L. In this type the lateral alignment is taken care of by the holes L, while the longitudinal alignment is taken care of by the holes T. Both sets of holes may have their "feeding walls" on the same transverse line as the feed pins, so that both sets of holes act as feeders.

This combination is especially valuable because the laterally elongated holes allow

for discrepancies caused by different widths appearing between the two rows of holes on the various copies of a set of forms. The longitudinally elongated holes permit the positive entrance of the feeding pins into the holes where considerable discrepancies appear in the spacing of the holes lengthwise of the forms with relation to each other in the superimposed webs.

- 10 I have found that this method of punching will permit me to operate an unlimited number of forms and maintain them in perfect alignment with each other and that it absolutely eliminates any possibility of the forms creeping away from each other or riding over the feed pins because of slight variations. Indeed, while in manifolding registers of the past it has been found almost impracticable to feed and align by pin wheel devices as many as six forms; with the above form of punching, the limit of forms is merely restricted to that number through with legible copies can be made.

15 I have heretofore explained the chief difficulties of handling a number of overlapped forms, as an example of the difficulty if a number of thin sheets of paper punched as for a loose-leaf book are taken, any one can see at once how hard it is to get all the holes 20 of a number of pieces into a true line. My invention enables an ordinary autographic register to be free of this difficulty, no matter how many forms are used, provided that the punching is done with a fair degree of accuracy.

25 In one sentence it may be said of this form that the laterally elongated holes maintain alignment longitudinally and provide for discrepancies laterally, and the longitudinally elongated holes maintain alignment laterally and provide for discrepancies longitudinally, while both sets of holes act as feeders.

30 My feeding devices will operate with the feeding walls or edges out of the true feeding line; i. e., where the feeding edges of the one row of holes is ahead of the feeding pins for that row. If the pins in the longitudinal elongated holes in such an instance 35 did not feed because of non-contact with the feeding edge of the holes, the pins would at least have plenty of clearance and not foul the paper, and the other pins in the other series of holes would properly feed without assistance.

35 However, should the operator abuse the feeding device, thus indenting the forward edges of the holes in the single series of holes that are actually doing the feeding 40 under this circumstance, by jerking the handle, or other means of abuse, such as laying the hand on the forms while being fed out, etc., the other pins would soon come in contact with the forward ends of the elongated holes—this contact of course depend-

ing upon the extent of the indentation in the forward end of the other holes necessary to bring about such contact—and as soon as this contact of the other series of pins takes place, feeding assistance will be given 45 to the other series of pins, thus bringing about normal feeding conditions before the forms can be torn, and thus improperly fed. This condition would be brought about by the combination of two or more series of 50 holes where one of the series was longitudinally elongated.

55 Figures 4 and 5 show graphically how in the printing of plural copies, differences in length and width of the forms, and hence 60 of the punching spaces may occur, due to imperfectly manufactured paper, and this is often the case. In Figure 4 the press paper web 10 is shown as printed into three sets of forms on lines 11, 12, and 13. The edge 14 65 of this press web is loose while the edge 15 is tight and hence in the printing or at least in the punching, the holes will not come in uniform spacing from each other lengthwise of the form, particularly when the 70 forms are slit apart and superimposed.

75 In Figure 5 is shown a press paper web 16 printed into forms 17, 18, and 19 and with a crease, fold, or wrinkle in the paper as at 20. The result of the crease will be that 80 when the paper is straightened out, as in rolling it into small rolls, after being slit from the wide press web, the spacing of the holes laterally as well as longitudinally of the individual webs will be at variance.

85 In the forms of punching in Figures 6 and 7, there are sets of holes T on both margins in the paper of Figure 6, while there are holes L on both margins in the form of Figure 7. As can be seen, these two forms will 90 operate with large numbers of webs of paper, but will not act to closely align the webs in the direction in which the holes are themselves extended. In the form in Figure 95 6 are shown two large holes 21 adapted to be engaged by large pins on a special rotary member on the feed shaft and will act occasionally to bring all the webs into lateral alignment. In the same way, large holes 22, 100 in the web in Figure 7, will act occasionally to align the superimposed webs longitudinally, as in my co-pending application Serial No. 161,940 filed April 14, 1917.

105 It will be noted that while I have described all of the holes for each set or longitudinal row as being the same throughout for that row, that this plan may be varied, so that taking Figure 3 for example, the row to the right may alternate holes T and holes L and the same for the row to the left. In 110 such a case I would prefer that the feeding walls of the holes be always on the true feeding line transverse the paper and that a horizontal and longitudinal hole will always be opposites for the two pin wheels. I do 115 120 125 130

not desire to be limited to the number of rows of holes, as any number more than one will be included in my invention.

Having thus described my invention, what

5 I claim as new and desire to secure by Letters Patent, is:—

1. A paper for manifolding use, which comprises webs of paper having a plurality of sets of consecutively arranged holes extending longitudinally of the webs, said holes having feeding walls in substantially fixed relation to each other and the boundary walls of the holes of different periphery in one row relative to corresponding holes in another row whereby allowance is made 10 for variations in the paper when fed by pin bearing feeding bodies having a fixed relation to each other.

2. A paper for manifolding use, which 20 comprises webs of paper having a plurality of sets of consecutively arranged holes extending longitudinally of the webs, said holes having feeding walls in substantially fixed relation to each other, and one of the 25 sets of holes, at least, having its dimensions widely variant transversely of the web from the size of the feeding pins which are to be employed, whereby allowance is made for variations in the paper when fed by pin bearing bodies having a fixed relation to each other.

3. A paper for manifolding use, which 35 comprises webs of paper having a plurality of sets of consecutively arranged holes extending longitudinally of the webs, same adapted for engaging a plurality of movable feeding pins fixedly positioned and spaced with relation to each other, one of said sets of holes having walls spaced transversely of 40 the webs to clear only slightly the sides of pins, and the other of said sets having walls to engage over the pins, but spaced transversely so as to widely clear the pins to the extent of being non-effective in maintaining 45 transverse arrangement.

4. A paper for manifolding use, which 50 comprises webs of paper having a plurality of sets of consecutively arranged holes extending longitudinally of the webs, same adapted for engaging a plurality of series of 55

one of said sets of holes having greater length than breadth and the other of said sets of holes having greater breadth than length.

5. A paper for manifolding use, which comprises webs of paper having a plurality of sets of consecutively arranged holes extending longitudinally of the webs, same adapted for engaging a plurality of series of 60 movable but fixedly related feeding pins, one of said sets of holes having greater length than breadth and the other of said sets of holes having greater breadth than length, and with the feeding walls of both 65 sorts of holes arranged on the feeding line of the pins.

6. A paper for manifolding use, which comprises webs of paper having a plurality of sets of consecutively arranged holes extending longitudinally of the webs adapted for engaging a plurality of series of movable but fixedly related feeding pins, said 70 holes being at least in part, of two sorts, 75 one sort having greater length than breadth, and the other sort having greater breadth than length.

7. A paper for manifolding use, which comprises webs of paper having a plurality of sets of consecutively arranged holes extending longitudinally of the webs adapted for engaging a plurality of series of movable but fixedly related feeding pins, said 80 holes being at least in part, of two sorts, one 85 sort having greater length than breadth, and the other sort having greater breadth than length, but with the feeding walls of all holes being positioned on the feeding line formed by drawing a line across the feeding 90 faces of the sets of pins.

8. A paper for manifolding use, which comprises webs of paper having a plurality of sets of consecutively arranged holes extending longitudinally of the webs, said 95 holes having boundary walls of different periphery in one row relative to corresponding holes in another row whereby allowance is made for variations in the paper when fed by pin bearing feeding bodies having a fixed relation to each other.

JOHN Q. SHERMAN.
